(57) **CLAIM**

The ornamental design for a pallet skirt display system, as shown and described.

DESCRIPTION

FIG. 1 illustrates a perspective view of an expandable pallet skirt (pallet skirt display system) in a storage or shipping configuration. The pallet skirt display system is resting on a plurality of pallets that form no part of the claimed design. The pallet skirt display system is interfaced with a removable shipper-cover that forms no part of the claimed design.

FIG. 2 illustrates a perspective view of the pallet skirt display system, wherein the removable shipper-cover illustrated in FIG. 1 has been removed. Racks, goods positioned within racks, and corner stabilizers form no part of the claimed design.

FIG. 3 illustrates a perspective view of the pallet skirt display system, wherein the flaps of the pallet skirt display system are folded downwardly to facilitate an alternate ornamental display configuration. The corner stabilizers shown in FIG. 2 have been removed.

FIG. 4 illustrates a perspective view of the pallet skirt display system in the ornamental display configuration.

FIG. 5 illustrates a perspective view of the pallet skirt display system in the ornamental display configuration with goods removed.

FIG. 6 illustrates a close-up perspective view of a convertible shelf and corner flap of the pallet skirt display system.

FIG. 7 illustrates a front or side view of the pallet skirt display system. Back and opposite side views are substantially identical and have been omitted; and,

FIG. 8 illustrates a top view of the pallet skirt display system.
